UNITED STATES PATENT OFFICE.

LOTHROP A. HAYDEN, OF CARVER, MASSACHUSETTS.

CRANBERRY-SEPARATOR.

SPECIFICATION forming part of Letters Patent No. 661,801, dated November 13, 1900.

Application filed January 30, 1900. Serial No. 3,274. (No model.)

To all whom it may concern:

Be it known that I, LOTHROP A. HAYDEN, a citizen of the United States, residing at South Carver, in the county of Plymouth and State 5 of Massachusetts, have invented a certain new and useful Improvement in Cranberry-Separators, of which the following is a specification.

This improvement relates to that class of 10 cranberry-separators in which the cranberries bound on a board, the good berries bounding high over a separating-board and the decayed or poor berries bounding but little and not over the separating-board, but falling elsewhere; and the invention or improvement 15 consists in certain novel constructions and arrangements of parts whereby the berries are prevented from becoming clogged and jammed either in the hopper or in their progress through the machine, whereby they are 20 more thoroughly separated into best berries, seconds, and rejected or worthless berries, whereby adjustability is provided in different parts, whereby the berries are prevented 25 from sticking to the boards, and whereby the apparatus is in other respects rendered more efficient.

The nature of the invention is fully described below and illustrated in the accompanying drawings, in which—

Figure 1 is a side view of a cranberry-separator embodying my invention. Fig. 2 is a vertical section of the same. Fig. 3 is a plan view of the device. Fig. 4 is a horizontal section taken on line 4, Fig. 1. Fig. 5 is a detail in horizontal section on line 5, Fig. 2.

Similar letters of reference indicate corresponding parts.

A A represent uprights, and A' A' cross- 40 pieces constituting the main frame, and a a' are uprights and cross-pieces constituting an extension thereof. In the lower part of the main frame are two boxes or receptacles B' and B'', and in the lower part of the extension 45 is a box B. The box B is for the reception of the good cranberries which pass through the apparatus, the box B' is for the seconds, and the box B'' is for the poor or rejected berries. Pivoted at C' to the upper cross-bar 50 of the frame is the hopper C, said hopper resting normally in a horizontal position on the pivots and on the bar C'', Figs. 1 and 2. The

open end of the hopper extends a short distance inside or between the upright walls D, supported by the frame, one of said walls being provided on its outer side with a guiding-loop b, through which a side bar b', bent outward at b'', extends, said side bar being pivotally secured at c to the hopper and having its outer end bent up into the lip b'', all as 60 shown in Figs. 1 and 3. The side bar is pivotally connected at d' with the bar d, whose lower end is pivotally secured at d'' to the frame. By this means the hopper may be raised and held at any desired angle by the 65 friction of the bar b' in the guiding-loop b and supported by the bar d. The inner surfaces of the upright boards D have secured to them a diagonally-arranged end board D', which, together with the guides D'', constitutes a diagonal slideway for the gate E, which has centrally secured to it at D''' a holder E', Fig. 2, pivotally secured at E'' to a lifting-bar E''', which is pivoted at one end to the end board D'. By sliding this gate in the ways 70 75 the width of the opening or gateway between it and the shaker is determined.

The shaker, which is lettered F, extends across the machine between the horizontal portion of the hopper C and the gate E, its 80 surface being set at an angle so that its highest edge is next and at about the same height as the bottom of the hopper, and its lower edge is next the gate or passage for the cranberries. One end of this shaker has secured to it a bar F', supporting a roller F'', which is engaged by the cam G, rigid on the shaft G', supported by the frame. This shaft is actuated by a suitable crank G'', and the roll is held in engagement with the cam by means 85 of a suitable spring g, secured to the frame and bearing against the opposite end of the shaker, as illustrated in Fig. 3. Rigid on the shaft G' is a gear-wheel h, Fig. 1, engaging with a gear-wheel h' on the shaft H', having its bearings in the frame. This shaft, in connection with a shaft H', located somewhat higher than the shaft H', and each carrying a roll I, carries the apron H beneath the entrance between the gate E and shaker F. 90 Guards I', Fig. 2, are supported by the frame at the opposite edges of the apron. The shaft H'' is supported by the lever J, pivotally secured at J' to a plate J'', adjustably secured 95 100

as to height to one of the uprights A of the frame by means of a bolt I'', extending through said upright and through a suitable slot in the plate. By this means the height 5 of the roll I on the shaft H'' is regulated and the angle of the apron H is determined. This apron is kept taut by means of a suitable spring i between the plate J'' and the lower end of the lever J.

10 K is a fan-blower supported in a suitable case K', from which a horizontal flue K'' extends. The fan is supported on a shaft k, which has a pulley k', connected by a belt k'' with the cam G.

15 When the berries are poured into the hopper, they run freely at whatever angle the hopper is placed, without danger of becoming bruised or jammed (as is the case with the wedge-shaped hoppers in common use) and

20 pass from the hopper upon the shaker, through the gateway or passage between said shaker and the gate E, onto the apron H, which is moved by the operator uphill or toward the outside of the machine. The berries while

25 on the apron are prevented from rolling over the edges by the guards I' and are subjected to a draft of air from the blower, directed through the flue K'' against the lower portion of the surface of the apron, for the purpose

30 of freeing the berries from the sand or dirt which has accompanied them through the hopper. The berries are then free to roll down the apron in a direction opposite from that of the movement of its surface and 35 against the draft of air from the blower into the throat or well through which the cranberries fall and in which they are separated.

The throat or well above referred to consists of an inclined passage between two parallel boards L, the upper ends of which are secured to the upper cross-bars A' and the lower ends secured to the oppositely-inclined walls L', supported by the cross-bars immediately above the receptacles B' B''.

40 45 P P represent a series of downwardly-inclined bounce-boards pivotally supported at their upper ends at R' to a guard or shield R and pivotally connected at their lower ends at R'' with ears R'' at the opposite ends of

50 vertical guide-boards P', whose ends are rigidly secured to the boards L. (See Fig. 5.) Opposite the guides P' are the dividing-boards S, each vertically set in slots S' in the boards L and adjustable vertically therein.

55 The tops of these dividing-boards are higher than the lower edges of the bounce-boards P, and their faces are parallel with the faces of the guides P', so that the passages between the boards S and P' are always vertical. The

60 upper edges of these dividing-boards are beveled or curved on their rear sides, as shown, and behind them are inclined shelves S'', secured at their opposite ends to the boards L and with their rear ends flush with similarly-

65 inclined cross-pieces T, having secured to them downwardly-inclined canvas guide-flaps T', said cross-pieces and flaps being sup-

ported by a trough or guard U, supported by the frame and parallel with the guard or shield R and the edges of the boards L. The 70 lower end of this trough U is flush with another similar trough U', whose lower end U'' is directly over the receptacle B and which is formed with a partition U''', so that at that point the trough is formed into a directing 75 nozzle or tube. Above the highest bounce-board P is a similar board P'', supported by a cross-bar or guide-bar V, and below the lowest of the four dividing-boards S is a reversely-placed bounce-board P''' and a dividing-board S'''. Under the bounce-board P''' is a vertical board W and guide-board W', and below and in front of the dividing-board S''' are guide-boards W'', underneath one of which is the vertical dividing-board Y. These 80 boards P''', S''', W', W'', and Y are supported by and between the upright boards L'. When the berries roll off the apron H, they first drop between the apron and the board V onto the upper bounce-board P. The best and sound 85 berries bound over the upper dividing-board S and are guided by the board S'', the canvas guides T' and trough U, and the tubular portion U''' into the receptacle U'' for sound and best berries. The berries which are not hard enough to bound over the highest dividing-board drop onto the next bounce-board P, and the soundest of them may bound over the dividing-board S opposite. Those berries which 90 are not sufficiently hard or sound to bound over any of the dividing-boards S fall upon the bounce-board P'', and the hardest of them jump over the dividing-board S''' and are guided by the boards W'' into the receptacle B'' for seconds. Those which have 95 passed between all the vertical passages formed by the boards P' and S and which upon striking the bounce-board P'' cannot 100 jump over the board S''' fall between said board S''' and the board W and thence between the boards W' and Y into the receptacle B'' for worthless or poorest berries. Of 105 course any earth or other foreign substance which accompanies the berries through the apparatus falls into this receptacle B''.

Should any berries fall on the highest board P'', they would probably be blown off the edge and drop upon the bounce-board P; but if they were heavy enough to roll down the 110 board P'' against the draft of air they would 115 pass down into the receptacle U'', being perfectly sound berries.

In order that the dividing-boards S may be moved vertically simultaneously and held in 120 the desired position in the slots S', they are pivotally secured at m to bars n, Fig. 1, provided with a number of horizontal pins n', adapted to be engaged by a hook n'', hung from the outside of one of the boards L. 125

The guide-board R has hinged to it at r' a hook r, which is caught over one of the pins n'', Fig. 1, extending horizontally from the board L. By moving this hook from one pin 130

to another the guide-board is raised or lowered and the angles of the bounce-boards P changed, said bounce-boards swinging from their inner pivots R".

5 The dividing-board S''' is held at the desired height in its slot by the arm l, pivoted at one end to said board and at the opposite end to the side board L', Fig. 4, a spring l' being secured at one end to the arm l and bearing at 10 its other end against the board L', the friction being sufficient to hold the dividing-board S''' in position. The board W' and one of the boards W'' are held in position between the two boards L' by means of springs 15 l'', secured at one end to the edges of the boards W' W'' and bearing at their opposite ends against the side boards L'. The mechanism l l'' may be duplicated at the opposite ends of the boards S''', W', and W''. Thus 20 the berries fall through a series of spaces which are always vertical and bound over vertical boards adjustable as to height. As the spaces through which the berries fall are not only vertical, but have parallel sides, there 25 is no possibility of their becoming crowded or wedged, and hence crushed or injured.

By providing the spring i the rolls I and apron H yield in case anything gets between a roll and the apron, thereby preventing injury to the apron.

Having thus fully described my invention, what I claim, and desire to secure by Letters Patent, is—

1. In a cranberry-separator of the character described, the frame; the boards L supported by the frame; the adjustable guide-board R provided with a hook adapted to engage with projections extending from the side of one of said boards; the vertical boards P' 35 rigidly secured to and between said boards L; the bounce-boards P pivotally connected

at their opposite ends to said vertical boards and to the guide-board R; the vertical dividing-boards S sliding in vertical slots in the boards L; and the bar n pivotally connected 45 with the dividing-boards and adapted to be supported at different heights by means of projections engaging with a hook on one of the boards L, substantially as described.

2. In a cranberry-separator of the character described, the frame; a well or chute containing suitable bounce-boards and dividing-boards; the shaft H' mounted in a frame and carrying a roll I; the supporting-lever J pivoted to the frame; the shaft H'' supported by 50 said lever and supporting the roll I'; the vertically-adjustable plate J'' supporting pivotally the lever J; the endless belt or apron H connecting said rolls; and a spring between the lower end of the lever and the plate whereby 55 said rolls are kept apart and the apron stretched, substantially as described.

3. In a cranberry-separator of the character described, the frame; a well or chute provided with suitable bounce-boards and dividing-boards; the structure D, D' mounted on the frame and provided with an opening or gateway leading to the well; the hopper C hinged at its inner edge to the frame near said opening or gateway; the guide-loop b secured to the outer side of one of the walls D of said structure; the side bar b' bent as described at b'' and formed into the lip b''', said side bar being pivotally secured at one end to the hopper and extending through said guide-loop; and the bar d pivotally secured at its 60 opposite ends to the frame and the side bar, substantially as described.
